(57) **CLAIM**

The ornamental design for a stuffing box bushing having a slit with a locking feature, as shown and described.

DESCRIPTION

FIG. 1 is a top perspective view of a stuffing box bushing having a slit with a locking feature showing my new design.; FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a top perspective view of the bushing showing the slit open.
The broken lines shown are for illustrative purposes only and form no part of the claimed design.
